SIPHON HEAD

Mortimer J. Brown, Niagara Falls, N. Y.

Application March 9, 1935, Serial No. 10,148

15 Claims. (Cl. 215—5)

This invention relates to siphon heads such as are used on siphon bottles for serving carbonated beverages, etc.; and has for its object to provide an improved siphon head with means for efficiently discharging the carbonated liquid and controlling the pressure in the vessel to which the head is applied.

Another object of the invention is to provide a siphon head which combines, in a single compact structure, means for controlling the admission of gas to a vessel to carbonate the liquid contents, a positive acting safety valve adapted to function automatically to relieve excess pressure within the vessel, a control member for operating said valve at will to discharge the carbonated liquid without transmitting the friction of said member to the valve itself, and means controlled by said valve for discharging the carbonated liquid with minimum disturbance so as to reduce the loss of gas as the liquid passes from the high pressure vessel to atmospheric pressure in the drinking glass.

Siphon bottles are often subjected to pressures which are not adequately controlled and as heretofore constructed have never been very widely used because not altogether safe or as efficient as they should be. Attempts have been made to provide safety valves for relieving excess pressure in such bottles but these have been objectionable because subject to corrosion and sticking, especially after long periods of inactivity. Discharge valves of the type heretofore employed to control the flow of liquid in siphon bottles would be of little or no use as safety valves because of the excessive friction and inertia of the manual operating mechanisms and the difficulty of operating same by pressure of the gas within the bottle.

In my siphon head I overcome these difficulties by combining a safety valve and a liquid control valve in one and the same structure which is necessarily operated whenever the siphon is used and due to such constant use is kept in prime operating condition at all times. Furthermore the valve as constructed in accordance with my invention has, to a dependable degree, the characteristics of a frictionless system and is disassociated from the manual operating mechanism so that it may be delicately balanced and adjusted to operate at any desired pressure without regard to the friction or inertia of said operating mechanism.

A further important feature of my siphon head resides in the provision of improved means for controlling the admission of gas to the bottle or vessel to carbonate the liquid contents as required.

One advantage of this construction is that it permits the liquid to be charged shortly before it is to be used, either with or without the addition of ice to the vessel, thus insuring a fresh drink charged and cooled to the taste of the individual. Still another feature of the invention resides in a novel construction and combination of discharge valve, nozzle and associated parts whereby the liquid when traveling at maximum velocity is spread in a rapidly moving film on a smooth braking surface with minimum turbulence so as to prolong its period of oversaturation and correspondingly enhance the character and taste of the beverage.

These and other features and advantages of the invention will be described in connection with the accompanying drawing, in which:

Fig. 1 is a longitudinal section through a siphon bottle and head embodying the invention;

Fig. 2 is an enlarged detail section taken on line 2—2 of Fig. 1; and

Fig. 3 is a broken longitudinal section illustrating a modification of the invention.

Referring to Figs. 1 and 2 of the drawing, 1 is a siphon head having an annular portion 2 which is internally threaded so that it may be screwed on the neck of a bottle 3 of any suitable type. An annular gasket 4 is clamped between the head 1 and the mouth of the bottle and has a depending ridge 5 for centering purposes.

The usual siphon tube 6, which reaches to a point adjacent the bottom of the bottle, is screwed into the siphon head 1 and communicates with a tubular orifice chamber 7 in the forward part of the head. A conical nozzle 8 of rubber or other suitable material is secured to and merges with a cylindrical cup 9 having a central opening 10 and a central annular flange 11 which is screwed into the chamber 7 in alignment with the nozzle. The opening 10 is controlled by a water-tight disc valve 12 of rubber or other suitable material which is secured to valve stem 13 as by a metal cap 14 having its peripheral edge spun over to grip and retain said valve material. Valve stem 13 extends through a star guide 15 in the flange 11 as shown in Fig. 2, and at its inner end has a blunt head 16 adapted to slide freely in the reduced rear portion 17 of chamber 7, said chamber portion 17 serving as a guide for the head 16. The valve stem carries coil spring 18 which is compressed between the star guide 15 and head 16 so as to hold the valve 12 securely on its seat, thereby closing the opening 10. In order to open the valve it is necessary to move same toward the left, as viewed in Fig. 1, against the tension of spring 18.

The valve 12 is operated by a rotatable con-

trol member 19 having an actuating knob or handle 20. In the form shown in Fig. 1, member 19 is threaded in a bushing 21 which, in turn, is screwed into the rear end of the siphon head in alignment with the chamber 7. The forward end 22 of said member 19 is reduced in diameter and projects into the rear portion 17 of chamber 7 adjacent and in alignment with the head 16 of the valve stem, passing through a packing gland 23 of cork or other suitable material which is clamped between the inner end of bushing 21 and the adjacent inner wall of the siphon head. The parts are preferably so arranged, and the pitch of the cooperating threads on control member 19 and bushing 21 so proportioned, that rotation of knob 20 for a fraction of a turn will cause the forward end 22 of said control member 19 to engage the head 16 of valve stem 13 and force said valve stem toward the left in Fig. 1 so as to move valve 12 off its seat against the tension of spring 18. By turning knob 20 a like distance in the opposite direction the member 19 will be withdrawn sufficiently to permit the valve 12 to close under the tension of spring 18.

From the foregoing it will be observed that the valve stem 13, star guides 15, head 16 of the valve stem, chamber 17 and control member 19 are all centered on the same axis. The face of valve 12 is true to a plane which is perpendicular to said axis, as is also the surface with which the face of valve 12 engages. The purpose of this construction is to reduce lateral movement of the valve stem to a minimum, thereby keeping the cooperating faces of the valve parallel with a minimum of frictional resistance at the guides 15 and 17. In this arrangement it will also be noted that the valve 12 and its actuating member 20 are at atmospheric pressure outside the siphon head and that only the reduced end 22 of the actuating member projects through packing gland 23 into the high pressure chamber of the head. All screw threads are outside the liquid-tight packing gland, hence it is possible to employ a push rod 22 which is small and accurately guided, and it is likewise easy to maintain a liquid-tight packing. The extension or push rod 22 of the actuating mechanism is preferably smooth or polished and carefully rounded, which facilitates the smooth working of the valve mechanism.

For charging the contents of the bottle 3 I provide a tubular fitting or nipple 24 which is screwed into the side of the siphon head and has its outer end threaded for connection to a tank or other source of carbon dioxide gas. Within said nipple 24 is a one-way valve 25 of the type employed in bicycle and other pneumatic tires, the purpose of said valve being to admit carbon dioxide gas to the siphon head and bottle while preventing same from passing out through said valve in the reverse direction.

One important use of my siphon head is on portable siphon bottles of the type employed for serving carbonated water, soft drinks, etc. at picnics and the like. To insure a fresh cold drink without prolonged packing in ice or storing in a refrigerator, the water is poured into the bottle together with cracked ice, the siphon head is screwed on and the nipple 24 of the head is connected to a tank or other source of carbon dioxide gas under pressure, the connection preferably being through a pressure control valve which holds the pressure constant. When the water is sufficiently charged the gas supply is disconnected and the freshly carbonated water is ready for use. The charging, of course, may take place

either before or after the water has been chilled, although there is an advantage in charging the water after chilling since water dissolves more carbon dioxide when cold.

In order to discharge the carbonated water it is simply necessary to turn the knob 20 to open valve 12 as previously described, causing the water to issue through siphon tube 6, chamber 7, valve opening 10 and nozzle 8. In the form shown, the carbonated water is delivered with minimum turbulence and loss of gas in accordance with the principle disclosed in my Patent #1,956,143 of April 24, 1934. To this end the chamber 7 serves to quiet the liquid stream issuing from the tube 6 while the inner face of valve 12 controls the rate of flow and helps to spread the liquid in a thin film.

The valve seat itself is continuous with and an extension of the curved polished braking surface 26 of the cup 9 which gradually merges into the conical collector or nozzle 8 extending substantially parallel to the direction of discharge, the entire discharge path thus constituting a continuous annular orifice without any obstruction which would cause eddies, or break or deflect the stream. In this way the outgoing liquid is held in continuous contact with the braking surface from the time and point it enters the opening 10 until its velocity is substantially reduced, avoiding all air gaps, impacts, turbulence, or mixing of previously discharged liquid with freshly discharged liquid, and thereby prolonging the period of oversaturation of the liquid at reduced pressure.

An important advantage of my siphon head is that the valve 12, in addition to controlling the normal discharge of liquid, also serves as a safety valve for relieving excess pressure at any time and at any needed rate. Theoretically a safety valve should open whenever a stated pressure is reached, but practically it is known that when safety valves are inactive for long periods of time they tend, because of corrosion, friction and sticking, to become sluggish and require more than the rated pressure to open them. This is particularly true in the case of a siphon bottle which is subject to the corrosive and contaminating action of many kinds of water solutions. I avoid this tendency to corrosion and sticking by operating the safety valve 12 every time the siphon is used, and by properly tensioning the spring 18 I enable the valve to open at any predetermined pressure. Another important advantage of my valve system is that the positive opening and closing of valve 12 is accomplished with minimum friction in the valve itself since the friction and inertia of the manual control member 19 and associated parts are effectively isolated from the valve 12. A further advantage of the construction illustrated in Fig. 1 is that it is possible, simply by pressing the stem of valve 25, to bleed off the gas pressure in the bottle without drawing water along with it.

In the embodiment shown in Fig. 3 the siphon tube 6' is carried by a disc-shaped gasket 4' which is clamped between the head 1 and the mouth of the bottle 3. The upper end of said tube 6' is connected to the tubular orifice chamber 7 by passage 27. In this construction, furthermore, the rotatable control member 19' has a hollow shank in which the one-way valve 25 is mounted. In charging the bottle of Fig. 3 the gas flows past valve 25' and through the shank of control member 19', chambers 17 and 7, passage 27 and tube 6' into the bottle 3. It is un-

derstood that the tension of spring 18 is such as to hold the valve 12 tightly closed during the charging operation. In other respects the siphon head of Fig. 3 is the same in construction and operation as that previously described.

Various other changes may also be made in the details of construction and mode of application of my siphon head without departing from the scope and spirit of the invention as defined in the appended claims.

The invention claimed is:

1. A siphon head comprising a chamber to be supplied with liquid under pressure, a valve on the low pressure side of said chamber operable to relieve excess pressure therein, a stem in said chamber supporting said valve, and a rotatable operating member threaded in said head in alignment with said stem and movable into and out of contact therewith to actuate said valve.
2. A siphon head comprising a chamber to be supplied with liquid under pressure, a valve on the low pressure side of said chamber operable to relieve excess pressure therein, means acting to close said valve, a stem in said chamber supporting said valve, a rotatable screw member threaded in said head adjacent and in alignment with the end of said stem, and means for rotating said member into and out of engagement with said stem to actuate said valve.
3. A siphon head comprising a chamber to be supplied with liquid under pressure and having an outlet forming a valve seat, a valve cooperating with said seat on the low pressure side of said chamber for relieving excess pressure therein, means acting to close said valve, a stem in said chamber supporting said valve, a packing gland in said head adjacent said chamber in alignment with said stem, a rotatable screw mechanism threaded in said head on the low pressure side of said gland, a shank carried by said screw mechanism extending through said gland adjacent and in alignment with the end of said stem, and means for rotating said screw mechanism to move said shank into and out of engagement with said stem to actuate said valve.
4. A siphon head comprising a chamber having an outlet forming a valve seat and a passage for connection to a siphon tube to discharge liquid under pressure through said chamber, a valve cooperating with said seat on the low pressure side of said chamber for relieving excess pressure therein, means acting to close said valve, a stem in said chamber supporting said valve, an operating member having a hollow shank extending into said chamber in alignment with the end of said stem, means for moving said chamber into and out of engagement with said stem to actuate said valve, and means for admitting gas through said shank to said chamber.
5. A siphon head comprising a chamber having an outlet forming a valve seat and a passage for connection to a siphon tube to discharge liquid under pressure through said chamber, a valve cooperating with said seat on the low pressure side of said chamber for relieving excess pressure therein, means acting to close said valve, a stem in said chamber supporting said valve, an operating member having a hollow shank extending into said chamber in alignment with the end of said stem, means for moving said member into and out of engagement with said stem to actuate said valve, means for connecting said member to a source of gas under pressure, and a valve in said shank controlling the admission of gas thereto.

6. A siphon head comprising a chamber having an outlet forming a valve seat and a passage for connection to a siphon tube to discharge liquid under pressure through said chamber, a valve cooperating with said seat on the low pressure side of said chamber for relieving excess pressure therein, means acting to close said valve, a stem in said chamber supporting said valve, a rotatable screw member threaded in said head having a hollow shank extending into said chamber adjacent and in alignment with the end of said stem, means for rotating said screw mechanism to move said shank into and out of engagement with said stem to actuate said valve, means for connecting said screw mechanism to a source of gas under pressure, and a valve in said shank controlling the admission of gas thereto.

7. A siphon head comprising a chamber having an outlet forming a valve seat and a passage for connection to a siphon tube to discharge liquid under pressure, a valve cooperating with said seat on the low pressure side of said chamber acting as a brake on the outgoing liquid, and a continuous unbroken braking surface extending outwardly from said valve seat substantially parallel to the direction of discharge to receive and hold the stream without impact or rebound until its velocity is substantially reduced.

8. A siphon head comprising a chamber having an outlet forming a valve seat and a passage for connection to a siphon tube to discharge liquid under pressure, a disc valve cooperating with said seat on the low pressure side of said chamber for braking and spreading the outgoing liquid in a thin annular film, and a continuous unbroken braking surface extending outwardly from said valve seat substantially parallel to the direction of discharge to receive and hold the stream without impact or rebound until its velocity is substantially reduced.

9. A siphon head comprising a chamber to be supplied with liquid under pressure, a valve on the low pressure side of said chamber operable to relieve excess pressure therein, a valve stem extending through the seat of said valve into said chamber, a spring coiled upon said valve stem under compression between the valve-seat and the head of said stem and acting to close said valve, an exclusively manually movable operating member carried by said siphon head on the opposite low pressure side of said chamber, a liquid-tight packing between said operating member and said chamber, and a smooth extension on said operating member extending through said packing into said chamber in position to engage and actuate said valve.

10. A siphon head comprising a chamber to be supplied with liquid under pressure, a valve and valve seat having parallel engaging surfaces on the low pressure side of said chamber, a valve stem secured to said valve and extending into said chamber on an axis perpendicular to said valve surfaces, tensioning means in said chamber acting on said stem to close said valve and permitting same to open to relieve excess pressure in said chamber, an operating member extending into said chamber in alignment with said stem, exclusively manually operated means for moving said operating member into and out of engagement with said stem to actuate said valve, said last named means being free of said spring, and an extension of said valve seat forming a braking surface extending substantially parallel to the direction of discharge to receive and hold the

stream in contact until its velocity is substantially reduced.

11. A siphon head comprising a chamber to be supplied with liquid under pressure, a valve for said chamber operable by, and adapted to relieve, excess pressure therein, means for manually operating said valve at will, and a smooth, continuous non-agitating braking surface disposed for reception of the liquid discharged through said valve and cooperating therewith to collect said liquid as a thin film in contact with said braking surface without impact or rebound for delivery to a receiving vessel.

12. A siphon head characterized by the elements combined and cooperating as set forth in claim 11, and further characterized by having said valve formed with a stem extending along the axis of operative movement of the valve, and by having said manually operating means formed as a push-rod supported independently of said valve stem whereby said valve is free of said manually operable means when operated by excess pressure.

13. A siphon head characterized by the elements combined and cooperating as set forth in claim 11, and further characterized by having

said valve formed with a stem and said manually operating means formed with a push rod both in alignment with the axis of operative movement of said valve, said push rod having a reduced portion working in a packing, and a relatively larger adjustment portion disposed on the low side of said packing.

14. A siphon head comprising a chamber maintained under high pressure, a discharge valve therefor, operable by and adapted to relieve excess pressure, a thrust member in said chamber adapted to operate said valve, and manual means to operate said thrust member, said valve being adapted to operate independently of said manual means.

15. A siphon head comprising a chamber maintained under high pressure, a discharge valve therefor, operable by and adapted to relieve excess pressure, a stem in said chamber supporting said valve, a manual operating member having a shank adjacent and in alignment with said stem for actuating the same, said valve being adapted to operate independently of said manual operating member.
